WELL PUMP

Howard J. Pankratz, Bartlesville, Okla., assignor
to Phillips Petroleum Company, a corporation
of Delaware

Application August 22, 1942, Serial No. 455,792

1 Claim. (Cl. 103—232)

My present invention relates to an improvement in pneumatic displacement oil well pumps.

More specifically, my invention resides in providing a valve of special characteristics which enables a pump such as disclosed in by co-pending application, now U. S. Patent 2,311,863, granted February 23, 1943, to be started or "kicked-off" at a much lower pressure than would be possible without its use. My invention also has further utility in that it provides means for draining the eduction or producing string of pipe so that the same may be pulled out of the well in an empty condition, should such removal become necessary or desirable for any reason.

While my invention has particular utility in connection with the particular pump structure referred to above, it is also of value in connection with draining the tubing string of other pumps which are known to the art.

It is an object to provide, in a deep well pump, means whereby the "kick-off" pressure required to begin normal operation of the pump may be reduced for any given starting conditions.

It is an object to provide inexpensive and reliable means by which the above result may be obtained.

It is a further object to facilitate the removal of the eduction tube string from wells equipped with pumps of the class described.

Other objects and advantages are to be realized by those skilled in the art from a consideration of the drawing forming part of this specification.

In the drawing, in which like numerals are used to designate like parts,

Figure 1 is a view of a well bore equipped with a pump of the class disclosed in my co-pending application previously referred to, and in which my present improvement is incorporated.

Figure 2 is an enlarged sectional view of my improvement which is the subject of the present application.

Figure 3 is a transverse section about the line 3—3 of Figure 2.

Referring more particularly to the drawing, in Figure 1 is shown a fragmentary view of a well bore having the casing 10 and a string of pressure tubing 11 having a pneumatic pump 12 inserted therein. A string of rotatable tubing 13 is provided for operation of the pump and also for conducting the produced oil to the surface of the ground all as described and disclosed in detail in my above mentioned co-pending Patent 2,311,863, to which reference should be had if complete details of the pump structure and operation are desired. For the present purposes, suffice it to

say that the pump 12 is fitted with a perforated bull plug 14 through which fluid in the well reservoir reaches the pump, via a standing check valve 15 and accumulation chamber 16. The tail pipe 17 is a continuation of tubing 13. The working parts of the pump consist of a multi-ported valve rotor (not shown) within the valve stator 18. In operation, gas supplied under pressure in tubing 11, by operation of the pump rotor ports, is made to lift the well fluid from accumulation chamber 16 to the surface via tubing 13. The fluid is lifted in successive "slugs" with alternate slugs of gas therebetween.

The amount of pressure required to lift the slugs of oil to the surface is proportional to the total head of fluid in tubing 13 at rest. The total head of fluid will be equal to the sum of the lengths of the several slugs, including gaseous slugs. For example, the head presented by a hundred slugs having an average length of two feet will be equivalent to the head of a solid column of the same fluid only 200 feet in height, even though the slugs may be distributed over a rise of a thousand feet or more. Hence, in wells of considerable depth, oil may be lifted to the surface with a gas pressure of relatively small magnitude, whereas an extremely high pressure would be necessary to lift a solid column of oil of an equal depth.

When installing a pump such as is illustrated in Figure 1, the tubing 11, containing the pump stator, is first lowered into the well casing to the desired depth. The smaller tubing 13 is then lowered, with the pump rotor valve attached. Since the desired elevation of the pump in the well bore may be considerably below the standing level of the oil (as level A—A, Figure 1), the tubing strings 11 and 13 will be full of oil to the same level.

In order to begin operation of the pump, it is necessary to clear the oil from the annular space between tubing 11 and 13, so that gas can reach the pump ports from the annulus as is required in the normal operation of the pump. The normal manner of clearing the annulus has been to apply sufficient gas pressure in the annulus to force all of the oil through the pump into the inner tubing string 13. However, the ratio of volumes per running foot of tubing between the inner and outer pipe strings (13 and 11, respectively) is such that an excessive head is built up by displacement into the smaller string and to clear the annulus, therefore, requires a very great pressure.

In a certain case within my knowledge, the oil

level A—A (Figure 1) was such that a bottom-hole pressure of 260 pounds per square inch was developed by the oil standing in the tubing. The ratio of cross-sectional areas of the annulus and of the inner tubing was in excess of 7 to 1. As a result, the oil displaced from the annulus to the center string was over seven times the amount originally contained therein, giving a total head in excess of eight times the original, or about 2100 pounds per square inch. By installing an unloading valve 19 in the tubing 13 (Figure 1), the "kick-off" pressure required to start pumping the well was reduced to less than 500 pounds per square inch.

Referring now to Figures 2 and 3, the details of my improvement are to be seen. The body 20 of my unloading valve may be machined from circular bar stock, and is bored longitudinally on different elements of a diameter to form two channels 21 and 22. The respective ends of body 20 are each bored concentrically for a short distance and are threaded internally as at 23 and 24, the diameter and pitch of the threads being appropriate for makeup in the tubing 13 (Figure 1). The ends may be threaded externally instead of internally, if desired, in which case makeup to the tubing would be had by means of couplings or collars.

In the lower end of channel 22 is threaded a bushing 25 having a bore 26. A closely fitted piston-like valve member 27, in channel 22, has a tapered portion 28 adapted to seat on the bore 26. A very light spring 29 is loaded between the back end of piston 27 and the threaded plug 30, the latter member being provided with a stem portion 31 to prevent collapse or deformation of the spring when compressed. In a portion of the adjacent wall, two ports 32 and 33 are bored in communication with channel 22. The lengths of stem 31 and piston 27 and the positions of ports 32 and 33 are so proportioned and arranged that piston 27 may travel upwardly in bore 22 far enough that piston 27 will be wholly above port 33; that is, piston 27 may lie entirely between ports 32 and 33, in which position both ports will be uncovered.

The valve being installed in tubing string 13 as shown in Figure 1, its operation will now be described, having reference to the various figures for that purpose.

As explained previously, the normal operation of the pump 12 requires that pressure (gas or air, as desired) be applied through casing 11, for the purpose of lifting the oil in the accumulation chamber 16 to the surface through tubing 13, all as explained previously herein, and as explained in my co-pending application referred to elsewhere in this specification. Since ports 32 and 33 are in communication with the interior of tubing 11, whatever gas pressure is contained therein will be imposed on the top of piston 27. At the same time, the lower end of piston 27 will be subjected to the pressure in tubing 13, by virtue of communication through channel 21 which is in effect a part of tubing string 13. This pressure will always be lower than that existing in tubing 11, due to the pressure drop incurred by passage of the gas or other medium from tubing 11 to tubing 13 through pump 12. The pressure drop in the pump is sizeable; therefore, the pressure unbalance above and below piston 27 will always act to keep the same closed during normal operation of the pump, and hence the valve has no effect whatever upon such operation.

In "kicking-off" the pump, however, my in-

vention is advantageous in that it permits the pump to be emptied at a much lower pressure than otherwise would be required.

As before explained, the conventional manner of "kicking-off" such a pump has been to displace the fluid standing in the well bore into the inner tubing string 13 by sheer force of pressure applied to the annulus between tubing strings 11 and 13. In the example cited, it was illustrated that, with a volumetric ratio of 7 to 1 between tubing in strings 11 and 13, the pressure head developed upon displacing all of the fluid into the smaller string was eight times the initial head of fluid standing in the well above the pump.

By use of my unloading device, it is now possible and entirely practical to clean the pump annulus by applying pressure to the small tubing, forcing all of the fluid into large tubing 11, and then gas-lifting the fluid to the surface in tubing 11 by continued application of pressure. In displacing the fluid from the smaller tubing to the larger, the developed pressure head in the example cited would be not eight times the initial head, but only $\frac{8}{7}$ times the initial head. Thus with the 260 pounds per square inch static bottom-hole pressure observed in the example, the pressure required to displace all of the fluid into the large tubing would be $\frac{8}{7} \times 260$ or 297 pounds per square inch required to displace the oil in the other direction.

Upon development of the 297 pounds per square inch pressure head required to displace all of the oil into the outer pipe string, a slight further increase of pressure will begin to gas-lift the fluid in a well-known manner and the outer string of pipe will shortly become emptied of fluid, since pressure in the tubing, being in excess of the formation pressure, will keep the standing valve 15 closed and thus will prevent any further fluid from entering the tubing from the well reservoir.

In this "kicking-off" operation, fluid is at first standing in the inner and outer tubing strings 13 and 11 at some level as A—A (Figure 1). The pressure on opposite sides of piston 27 is, therefore, equal. As soon as the pressure applied to inner tubing 13 begins to unbalance the system, piston 27 begins to rise or open. Due to the close fit of the piston in its cylindrical bore 22, only a very small differential pressure is required to lift it above port 33, so that the fluid in tubing 13 and channel 21 will immediately begin flowing through port 33 to outer tubing 11. Port 32 is provided as an exhaust or relief so that piston 27 may rise freely in bore 22.

It is to be understood that spring 29 is to be made so "soft" or "weak" that it presents no appreciable resistance to the rise of piston 27 when the latter is pressurized from below. The spring 29 is supplied simply to serve as a stabilizer or shock absorber to prevent fluttering or chattering of the piston on its seat in bushing 25 as the valve is lowered into the well through any fluid that might be standing therein when the valve and tubing string 13 are installed. I have tested my device in a well with the spring 29 omitted, and have found that piston 27 remains seated in a satisfactory manner while pumping, the valve being held closed by difference of pressure in tubing 11 and 13 alone.

After "kicking off" the well in the manner above described, the gas pressure is cut off from tubing 13 and re-applied to outer tubing 11 for operation of pump 12 in the conventional prescribed manner.

It is further to be understood that, while the pressure required to gas-lift the oil in the kicking-off operation need only be slightly in excess of 297-300 pounds per square inch in the example cited, somewhat higher pressure is desirable to execute the kick-off operation quickly. This is partly due to the well-known fact that the "slippage" in gas-lifting through an annulus is quite high, and this type of gas-lift operation would be inefficient for continuous production purposes. In the test example, a pressure between 400 and 500 pounds per square inch was found adequate to kick off the well, whereas 2100-2200 pounds per square inch was formerly required before installation of the unloading valve. It should be pointed out in this connection that gas-lifting the annulus fluid in the manner herein described is practically impossible without the use of my valve, since the orifice opening in the pump 12 is too small to allow sufficient flow of gas for lifting of the oil could not be had simply by applying pressure to the inner string and passing it through the pump ports to the annulus.

In pulling the inner string of tubing, for purposes of repairing the pump rotor, for example, my valve is useful in that the fluid standing in the tubing will automatically be drained into the larger tubing 11, permitting the inner tubing to be pulled "dry." The construction of pump 12 is such that the tubing would otherwise have to be pulled "wet," thus adding to the total weight

to be lifted by the amount of fluid contained in the tubing.

It is understood that many variations in structure of my unloading valve may be made within the scope of my invention. Having described the novel utility of my invention as well as a preferred form of structure for the same, the following sub-joined claim is set forth.

I claim:

10 An unloading valve for the purposes herein described comprising a body member having a through passage therein, a second passage in said body member having one end in communication with the first passage at its lower end, an upper port and a lower port communicating between the second passage and the outside of said body member, a valve seat in said second passage below both of said ports and a valve member closing said seat and movable to uncover said lower port, a helical compression spring urging said valve member to said seat and a spacing member extending inside said spring along the axis of said helix a sufficient distance to prevent said valve member from covering the upper one of said ports, and to prevent complete compression of said spring whereby the valve operates freely and positively at all times, and the spring is better able to resist fatigue than if it were completely compressed, regardless of the opening 25 pressure.

HOWARD J. PANKRATZ.
